UNITED STATES PATENT OFFICE

136,748

DESIGN FOR A TEXTILE FABRIC OR SIMILAR ARTICLE OF MANUFACTURE

Walter G. Tilbrook, Brooklyn, N. Y.

Application May 28, 1943, Serial No. 110,320

Term of patent 3½ years

To all whom it may concern:

Be it known that I, Walter G. Tilbrook, a citizen of Great Britain, residing in Brooklyn, county of Kings and State of New York, have invented a new, original, and ornamental Design for a Textile fabric or similar article of manufacture, of which the following is a specification, reference being had to the accompanying drawing forming a part thereof.

The drawing is a plan view of a textile fabric showing the complete width of my new design. The dot and dash lines on the drawing outline substantially the design unit, which unit may be repeated in regular succession as indicated by an extension beyond one of the unit boundaries.

I claim:

The ornamental design for a textile fabric or similar article of manufacture as shown and described.

WALTER G. TILBROOK.
